UNITED STATES PATENT OFFICE

DONALD S. BARROWS, OF ROCHESTER, NEW YORK

CAR DOOR FASTENER

Application filed December 29, 1926, Serial No. 157,716. Renewed December 10, 1930.

This invention relates to car door fasteners and, more particularly, to such applicable to the sliding doors of railway freight cars to prevent access of burglars to such cars.

5 The principal object of my invention, generally considered, is the provision of a fastener for sliding side doors of freight cars adapted to be applied at the bottom edge at the center or intermediate portion of said 10 door and cooperate with a bracket preferably extending from an adjacent sill, said bracket being formed with an aperture for receiving a fastening bolt from the housing of the fastener and provided with means for limiting 15 transverse motion of said door while permitting longitudinal motion thereof, the housing of said fastener being also formed with a transverse aperture preferably adapted to receive an anvil block embracingly associated with the fastening bolt, both of said 20 members being adapted to be riveted to each other and, if desired, to the housing and so hold the door in closed position.

An object of my invention is the provision 25 of a fastener adapted for application at the lower edge of a sliding freight car door, said fastener comprising a housing slidably receiving a normally upright fastening bar, the lower end of said fastening bar being 30 adapted for reception in a bracket extending from an adjacent sill of the car and formed with a portion lying outside of the lower edge of the car door to prevent outward motion of said door.

35 Another object of my invention is the provision of a fastener preferably adapted for application to the lower edge of a sliding freight car door, said fastener comprising a housing adapted for connection to the door and adapted to slidably receive a fastening bolt, the lower end of said bolt being received 40 in a member fixed to an adjacent portion of the car underframe, an anvil block received in a transverse aperture in said housing and normally embracing the upper portion of said fastening bolt, said block and bolt being, when in fastened position, connected to the housing by means of a rivet passing through said housing, block and bolt and headed over to make it impossible to remove the fastening

bolt without considerable noise while cutting the rivet.

Other objects and advantages of the invention relating to the particular arrangement and combination of the various parts will become apparent as the description proceeds.

55 Referring to the drawings illustrating my invention, the scope whereof is defined by the appended claims:

Figure 1 is a side elevation of a portion of 60 a box car showing one embodiment of my invention applied thereto.

Figure 2 is a side elevation of the fastener on a larger scale.

Figure 3 is a transverse section through a 65 portion of the car door and underframe showing the fastener in end elevation.

Figure 4 is a detail view of the locking rivet bushing or anvil block.

70 Referring to the drawings in detail, like parts being designated by like reference characters, the illustrated embodiment of my car door fastener comprises a housing or casing 1 adapted to be attached to the door 2 of the car by a plurality of rivets or other attaching means 3. The door 2 is shown as formed with a Z-bar 4, one flange of which extends outwardly of the lower portion of the door 2 and the other flange of which forms a downward extension 5 from the lower portion of the door, the inner surface of said downward extension preferably being flush with the inside of the door, as illustrated particularly in Figure 3. The base or side portion 6 of the housing 1 is preferably formed to correspond with the construction adjacent the lower part of the door and so, in the present embodiment, is offset as indicated at 7 to provide for the reception of the upper flange of the Z-bar 4 between the base 6 and the door 2.

75 The housing 1 is formed with a passage-way 8 which is longitudinal or normally upright as indicated and is adapted for the reception of the fastening bolt or bar 9, the upper end of which is preferably headed as indicated at 10 and formed with an apertured lug 11 normally disposed adjacent a similar lug 12 on the housing 1 for the reception of the usual form of seal (not shown). The

housing 1 is preferably formed with a transverse or normally horizontal aperture 13 for the reception of a fastening rivet 14. Said aperture 13 is preferably enlarged to one side as indicated at 15 for receiving an anvil block or rivet bushing 16, said bushing being preferably U-shaped in cross section, as illustrated most clearly in Figure 4, and adapted to embrace or partially surround the fastening bolt 9. If desired, the side web to the left of the bushing 16 may be omitted so that the transverse aperture is uniform in cross section. The enlarged portion 15 of the aperture is formed of sufficient size to receive the bushing 16 before the fastening bolt is inserted and, when inserted in place, said fastening bolt prevents removal of the bushing. After the bushing and fastening bolt have been inserted in place, as indicated most clearly in Figures 2 and 3, the rivet 14 is then preferably inserted from the left, as viewed in Figure 2, and headed over at the opposite end as indicated at 17.

In order to facilitate heading over the other end of the rivet, the housing 1 is preferably formed with a transverse wall 18 extending from the base 6 and joining with the outwardly extending portion of the housing, providing for the reception of the fastening bar 9, by a longitudinal wall or web 19 forming a pocket 20 adapted to receive a bucking bar or the like (not shown), which is held in said pocket against the head of the rivet when riveting over the other end thereof. In order to limit vertical movement of the fastening bar 9, the same is preferably formed with a transverse stop pin 21, the ends of which are received in corresponding grooves 22 and 23 on the interior of the housing to allow raising and lowering of the bar 9 to the desired degree yet normally prevent complete withdrawal thereof.

The lower end of the fastening bolt 9 is received in a bracket or keeper 24 when in fastened position, said keeper being constructed to correspond with the car to which applied and, in the embodiment illustrated, being connected to the web 25 of the adjacent side sill of the car by a plurality of rivets 26. The bracket 24 extends toward the lower edge of the door and is preferably formed with an upright web or flange 27 extending outside of the lower edge of the door 2 or the flange 5 of the Z-bar 4 thereof, thereby preventing transverse or sidewise motion of the door. The upper edge of said flange or web 27 is continued horizontally as a flange 28 beneath the housing 1 of the fastener and formed with an aperture 29 adapted to register with the fastening bolt receiving aperture of the housing and serve for the reception of the lower end of said bolt when the door is in fastened position. The lower end of the fastening bolt 9 is preferably formed with one or more apertures 30 normally dis-

posed below the flange 28 of the bracket 24 and adapted to register with a corresponding aperture 31 in the upright web or flange 32 of the bracket 24 and receive the usual form of sealing means (not shown).

From the foregoing, it will be seen that I have provided a fastener which is preferably applied to the middle of the door at the bottom and replaces the usual fastener which is on the left-hand door post. The bracket 24, which engages the lower end of the bolt 9, replaces one of the usual bottom guides and, therefore, the upright portion 27 may be formed to correspond with the usual guiding portion of a bottom guide. The object in locating the fastener at the middle of the door at the bottom is to prevent anyone, such as a burglar, having access to the car as, when a door is fastened at the left, it is possible to remove one bolt, if the guides are bolted to the car, from each of the center and right-hand guides, swing the guides down so that they clear the door and then spring the door outwardly enough to gain entrance. With the fastener at the middle of the door, as illustrated, the framing is stiff enough to prevent anyone from springing either the right or left lower corner of the door. The fastening rivet block or bushing is preferably employed to facilitate heading over the end of the rivet, as it gives a greater thickness of metal to hammer against and avoids damage to the housing 1.

Having now described my invention, I claim:

1. A fastener comprising a housing adapted to be secured to the bottom of a car door, intermediate the corners thereof, having a normally upright passage therethrough and a transverse aperture intersecting said passage, a bracket adapted to be secured to an adjacent sill of the car and having a portion lying outside the lower edge of said door to limit transverse motion thereof, and a substantially horizontal extension beyond said portion and provided with an opening therein adapted to register with said passage, a fastening bolt adapted to occupy said passage and opening and having a transverse aperture therethrough and a rivet adapted to be passed through the transverse aperture in the housing and bolt and headed over to prevent withdrawal of said bolt.

2. A fastener comprising a housing adapted to be secured to a car door and having a normally upright passage therethrough, a transverse aperture intersecting said passage, a bracket adapted to be secured to the adjacent car sill and having an opening adapted to register with said passage when the door is closed, an anvil block adapted for insertion in said transverse aperture, a fastening bolt adapted to occupy said passage and opening and having a transverse aperture therethrough, said anvil block being formed to

embrace said bolt when in place and provided with apertures therethrough registering with the aperture in the housing and bolt and a rivet adapted to be passed through said housing, anvil block and bolt and headed over to prevent its withdrawal.

3. A fastener comprising a housing having a longitudinal passage therethrough and a transverse hole intersecting said passage, a bracket having a substantially upright portion lying outside of the lower edge of said door to prevent transverse movement thereof and having an opening adapted to register with said passage, a fastening bolt adapted to occupy said passage and opening and having a transverse hole therethrough adapted to register with said first-mentioned hole, a rivet adapted to be passed through said holes and headed over, and a web on said housing to provide a pocket for receiving a bucking bar for heading over said rivet.

4. A fastener comprising a housing adapted to be secured to a car door and having a normally upright opening therethrough and a transverse aperture intersecting said opening, a bracket adapted to be secured to an adjacent sill of the car and formed to function as a bottom guide for the door and provided with an extension outwardly of the guiding portion formed with an opening therein registering with the opening in the housing when the door is closed, a fastening member adapted to occupy the opening in the housing and engage in the opening in the bracket and having a transverse aperture therethrough, said bolt and housing being adapted to receive a rivet through the transverse apertures therein whereby, when the same is headed over, withdrawal of the fastening member is prevented.

5. A fastener comprising a housing adapted to be secured to a car door and having a normally upright passage therethrough, a transverse aperture intersecting said passage, a bracket normally secured to an adjacent sill of the car and having an opening registering with said passage when the door is closed, a U-shaped block insertable in said transverse aperture, a fastening bolt insertable in the upright passage in the housing and embraced between the arms of the U-shaped block, said block and bolt being formed with apertures therethrough registering with the aperture in the housing, whereby a rivet may be passed through all of said transverse apertures and headed over to prevent withdrawal of the bolt.

6. A fastener comprising a housing having a longitudinal passage therethrough and a transverse hole intersecting said passage, a bracket having a substantially upright portion normally lying beyond the lower edge of an associated door to limit transverse movement thereof, an extension on said portion provided with an opening adapted to register

with the passage in the housing, an anvil block normally received in the transverse hole in the housing and formed with arms lying outside of the line of the longitudinal passage, a fastening bolt insertable in said passage between the arms of said block, said block and bolt being formed with registering apertures adapted to receive a rivet for preventing withdrawal of the bolt.

7. A fastener adapted for use on a sliding car, said fastener comprising a housing adapted to be secured to the car door adjacent the center of the lower edge thereof, a bolt vertically slidable in said housing, a bracket adapted to be secured to the adjacent sill of the car and formed with a portion apertured for the reception of the bolt when the door is in closed position, said housing being formed with a transverse aperture receiving a member normally embracing said bolt, said member and bolt being formed with registering apertures for receiving a rivet to hold the bolt in fastened position.

In testimony whereof I affix my signature.

DONALD S. BARROWS.
